PLASTIC SHEET MATERIAL OR SIMILAR ARTICLE

Harry A. Shortway, Glen Rock, and Peter Zevas, Newark, N.J., assignors to Congoleum-Nairn Inc., Kearny, N.J., a corporation of New York

Filed Mar. 20, 1961, Ser. No. 64,384

Term of patent 14 years

(Cl. D87—3)

A design unit is enclosed within the dot and dash lines which unit is repeated in regular succession as indicated by the extensions beyond the unit boundaries.

We claim:

The ornamental design for a plastic sheet material or similar article, substantially as shown and described.
